Francesco Collura, New York, N. Y., assignor to
American Optical Company, Southbridge,
Mass., a voluntary association of Massachusetts

Application May 19, 1950, Serial No. 10,047

Term of patent 14 years

(Cl. D15—2)

To all whom it may concern:

Be it known that I, Francesco Collura, a citizen of the United States of America, residing at New York, in the county of New York, and State of New York, have invented a new, original, and ornamental Design for an Adjustable Chair, of which the following is a specification, reference being made to the accompanying drawing, forming a part thereof.

The figure of the drawing is a perspective view of an adjustable chair showing my new design.

The characteristic features of my new design are shown in full lines in the drawing.

I claim:

The ornamental design for an adjustable chair, substantially as shown and described.

FRANCESCO COLLURA.
